LIFTING JACK

William A. Traut, Racine, Wis., assignor to
Walker Manufacturing Company, Racine,
Wis., a corporation of Wisconsin

Application September 19, 1930
Serial No. 483,042

10 Claims. (Cl. 254—102)

This invention relates to certain new and useful improvements in lifting jacks, and more particularly to a screw jack of the multiple extension type, designed to be capable of extension 5 to more than twice the height of the jack when in lowered or collapsed position.

The jack comprises three substantially cylindrical members adapted to telescope within one another when in collapsed position. Means is 10 provided for rotating the intermediate member, whereas the upper and lower members are linked together by an extensible means so that both will be held from rotation when the lower or supporting member is resting upon the ground. 15 Inter-engaging screw members housed within the cylindrical members cause the intermediate member to be moved vertically within the lower member, and the upper member to be moved vertically within the intermediate member, whenever the intermediate member is rotated. 20

The general object of this invention is to provide an improved jack of the type briefly described hereinabove and disclosed more in detail in the specifications which follow.

Another object is to provide a telescopic jack of the screw type in which all of the screw members are completely housed within the telescopic lifting members.

Another object is to provide an improved jack 30 of this type in which the members may be completely elevated or lowered even though no load is carried by the jack.

Another object is to provide improved means for frictionally resisting rotation of the intermediate or driving member.

Another object is to provide a jack of this type which is simple and economical to manufacture and easily assembled.

Other objects and advantages of this invention will be more apparent from the following detailed description of one approved form of jack built according to the principles of this invention.

In the accompanying drawings:

Fig. 1 is a central vertical section through the jack in elevated or extended position.

Fig. 2 is a side elevation, partially in vertical section, of the jack in lowered or collapsed position.

Fig. 3 is a horizontal section taken substantially on the line 3—3 of Fig. 1.

Fig. 4 is a horizontal section taken substantially on the line 4—4 of Fig. 1.

Fig. 5 is a perspective view of the intermediate lifting member.

Fig. 6 is a perspective view of the upper portion of the upper lifting member, with the lifting cap removed.

Fig. 7 is a perspective view of the upper sliding key member.

Fig. 8 is a perspective view of the split or sectional ring or collar used in the top of the standard.

The jack comprises a lower member A in the form of a supporting base or standard, an upper lifting member B and an intermediate lifting member C, the three members A, B and C being substantially in the form of hollow cylinders adapted to telescope within one another and forming a substantially closed housing in any 70 position of the jack.

The lower or base member A comprises a main casting formed with an upwardly extending substantially cylindrical shell 1 enclosing a vertical cylindrical chamber 2 which extends through the upper end of the jack but is closed at the bottom 3. This closed bottom 3 extends outwardly in the form of a base plate 4 which is reinforced by the vertical webs 5. A thickened annular portion or collar 6 at the upper end of member A 80 is centrally recessed to receive a split spring locking ring 7, and at diametrically opposite points is provided with cylindrical openings 8 to receive the cylindrical friction plugs or disks 9. An internal annular shoulder or collar is 85 formed by a split or sectional ring consisting of similar sections 10 (Fig. 8) each provided with an opening 11 adapted to receive one of the friction disks 9.

A vertically extending central hollow screw 12 90 is externally threaded and is fixedly supported in the bottom 3 of base member A by being screwed thereinto as indicated at 13 and secured in place by means of a suitable key 14. The member 12 is interiorly hollow as indicated at 95 15, the lower end of this opening being closed by a suitable plug or closure plate 16. The main bore 15 does not extend through the upper end or head 17 of screw 12, this head 17 being provided with a non-circular opening to receive the vertically slideable post member 18. As here shown, post 18 is of hexagonal cross section and is slideable through a similarly shaped opening in head 17 so that the post 18 will at all times be held from rotation by 105 the stationary screw 12. A cross pin 19 in the lower end of post 18 is adapted to engage the lower face of head 17 and limit the upward movement of the post 18.

The intermediate member C comprises a hol- 110

low shell which is exteriorly cylindrical at 20 and is formed with an interior cylindrical chamber 21 which extends through the upper end of the member C but is partially closed at the bottom by the inwardly extending flange or collar 22. An outwardly extending annular collar 23 at the lower end of member C is adapted to slidably engage within chamber 21 in the lower member A. This collar 23 also engages the lower surface of split collar 10 to limit the upward movement of intermediate member C. A hollow exteriorly threaded screw sleeve 24 is positioned coaxially within member C and is non-rotatably fixed thereto by being keyed at its lower end within the inwardly extending flange portion 22 as indicated at 25. The lower portion of sleeve 24 is internally threaded to form a nut 26 which meshes with the lower fixed screw 12. The upper portion of sleeve 24, above the nut 26, is interiorly cylindrical as indicated at 27 so as to freely telescope over the fixed screw 12 when the jack is lowered.

The upper lifting member B is in the form of a hollow shell which is exteriorly cylindrical at 28 so as to telescope slidably and rotatably within the chamber or cavity 21 in the intermediate member C. The lower portion of member B is internally threaded to form a nut 29 meshing with the exterior threads on sleeve 24. The cavity or chamber 30 within the upper portion of member B is of any suitable non-circular cross section so as to non-rotatably but slidably engage with a key member 31 which is secured as by means of pin 31' to the upper end of post 18. In the form here shown, the key 31 is in the form of a hexagonal plate or washer, and vertically extending grooves 32 are formed in the otherwise cylindrical interior 30 of member B to engage with the corners of the hexagonal key 31. Any other suitable form of keying means may be provided so that the post 18 is permitted vertical sliding movement with relation to member B but relative rotation of these members is prevented. A load-supporting cap 50 is secured within the upper end of member B by any suitable means such as pin 51.

Any suitable means may be provided for rotating the intermediate member C in either direction. As here shown, an outwardly extending collar 33 at the upper end of member C is formed with an annular series of ratchet teeth 34. A pawl housing is formed of similar upper and lower plates 35 and 36 each comprising an annular portion 37 which fits in an annular groove 38, formed one at the top and one at the bottom of flange 33. At one side the members 35 and 36 are extended to form a handle-receiving socket 39, the members 35 and 36 being secured together at each side of socket 39 as by means of rivets 40. A double armed pawl 41 is centrally pivoted on pin 42 riveted between the housing members 35 and 36, pawl 41 being formed with similar teeth 43 and 44 at its opposite ends adapted to engage alternatively with the ratchet teeth 34 on member C. A cam or finger 45 projecting rearwardly from the central portion of pawl 41 engages with a suitable leaf spring 46 mounted within the pawl housing. The pawl 41 is provided with similar oppositely extending fingers 47 and 48 by means of which either tooth 43 or 44 may be alternatively thrown into engagement with the ratchet teeth 34. The spring 46 acting against the cam 45 will hold this tooth 43 or 44 yieldably in engagement with the ratchet teeth 34 and permit it to ride freely over the teeth 34

in one direction. A handle 49 may be detachably engaged within the socket 39. With the parts positioned as shown in Fig. 3, if handle 49 is oscillated about the central vertical axis of the jack, it will be apparent that the ratchet wheel 34 and intermediate member C will be intermittently rotated in a counter-clockwise direction. By properly manipulating one of the fingers 47 or 48, the other tooth 44 of pawl 41 could be thrown into engagement with teeth 34, whereupon a similar oscillating movement of handle 49 would impart an intermittent clockwise rotation to the intermediate member C.

In operation, assuming that the jack is in the collapsed position shown in Fig. 2, and that the reversing pawl 41 is properly positioned, oscillation of handle 49 will cause the intermediate member C to be intermittently rotated in such a direction that the nut 26 fixed in the lower end of this member C will travel upwardly on the fixed screw 12 in standard or base member A, thereby moving the intermediate member C vertically out of the standard. At the same time, the external threads of sleeve 24 (which rotates with the member C) will travel downwardly through nut 29 in upper member B thus causing this upper lifting member B to be moved upwardly out of the intermediate member C. The member B, and consequently the nut 29 fixed in the lower end thereof, will at all times be prevented from rotation by means of its non-rotatable but extensible connection with the base member A through key 31, post 18, and fixed screw 12. This operation will continue until the jack reaches the extreme elevated position shown in Fig. 1. Upward movement of intermediate member C is limited by the engagement of collar 23 at the lower end of member C with the split collar 10 fixed within the upper member of base member A. Upward movement of upper lifting member B is limited by the engagement of key 31 with the upper surface of nut 29 and the engagement of pin 19 at the lower end of post 18 with the head 17 in fixed screw 12. It will thus be apparent that the telescoping cylindrical members A, B and C cannot be entirely withdrawn from one another after the jack is assembled, unless it is desired to disconnect the parts for repair purposes.

The friction disks or plugs 9 not only serve to hold the split collar 10 in place and thus limit the upward movement of intermediate member C, but these plugs also frictionally engage the outer cylindrical surface 20 of member C at all times due to the pressure of spring ring 7. The frictional resistance thus offered is sufficient to hold the member C against rotation during the idle stroke of handle 49 while the pawl 41 is running over the ratchet teeth 34, and also serves to snugly hold the intermediate member C in position within the standard A at all times.

The jack may be assembled by first mounting the fixed screw 12 within the base member A, and similarly mounting the fixed screw sleeve 24 within the intermediate member C. The intermediate member C is then inserted through the upper end of base member A by screwing nut 26 downwardly upon the fixed screw 12. When the intermediate member C has been thus inserted a sufficient distance within standard A, the sections of split collar 10 may be inserted within the upper end of standard A around the cylindrical surface of intermediate member C, and the friction plugs or disks 9 inserted and locked in position by means of spring ring 7. 150

The member C is then screwed completely down within the standard A, and the member B (without cap 50) is screwed down within member C about the sleeve 24. The assembled key 31 and post 18 are then inserted through the upper end of the collapsed jack members. The post will extend through the base plate 4 and the stop pin 19 is inserted in the lower end of post 18 and the post pushed back into the assembled 5 jack and closure plate 16 secured in place. The cap 50 can now be secured in the upper end of member B, and the screw members are completely enclosed.

It will now be seen that the jack is in the 10 form of a completely closed telescopic housing at all times. All of the screw members are completely housed within the telescopic cylindrical members, as is also the means for preventing rotation of the upper lifting member B. There 15 are no external screw threads on any of the housing members A, B or C. This assembly may be partially filled with grease so as to be self-lubricating.

An old and well-known form of ratchet driving means has been disclosed for rotating the 20 intermediate member C. While this means is entirely suitable for this purpose, it will be understood that any other suitable form of driving means could be substituted for imparting the 25 necessary rotation to the member C.

As long as the base member A is resting upon the ground or other suitable support so that it is prevented from rotation, the upper member B will also be prevented from rotation by the extensible means hereinabove described, so that 30 the jack can be completely elevated or lowered without the presence of any load upon the lifting head 50. This permits the jack to be easily adjusted beneath a load of any height (within the limits of the jack's lift), and permits the 35 jack to be sufficiently lowered to permit its easy removal, even after the load has been disengaged.

I claim:

1. A lifting jack comprising upper, lower and intermediate hollow members, the lower member being in the form of a supporting base and the upper member adapted to support a load, said upper member telescoping slidably within the intermediate member and the intermediate member telescoping slidably within the base member, extensible means confined within the hollow members and connecting the upper member with the base member for preventing rotation of the upper member, means mounted on and moving vertically with the intermediate members for rotating the intermediate member, an internally threaded nut fixed within the lower portion of the upper member, an internally 40 and externally threaded screw sleeve fixed within the intermediate member and meshing within the nut, and an externally threaded screw fixed within the base member and meshing within the screw sleeve.

2. A lifting jack comprising upper, lower and intermediate hollow members, the lower member being in the form of a supporting base and the upper member adapted to support a load, said upper member telescoping slidably within the intermediate member and the intermediate member telescoping slidably within the base member, means mounted on and moving vertically with the intermediate member for rotating the intermediate member, an internally threaded 45 nut fixed within the lower portion of the upper

member, an internally and externally threaded screw sleeve fixed within the intermediate member and meshing within the nut, a hollow externally threaded screw fixed within the base member and meshing within the screw sleeve, 50 and an inner post member slidably but non-rotatably keyed at its respective end portions within the hollow screw and the upper hollow member.

3. A lifting jack comprising upper, lower and intermediate hollow members, the lower member being in the form of a supporting base and the upper member adapted to support a load, said intermediate member telescoping slidably and rotatably within the base member, and the upper member telescoping slidably and rotatably within the intermediate member, means for rotating the intermediate member, means housed within the hollow members for causing the intermediate member to be moved vertically with 55 relation to the base member and the upper member to be moved vertically with relation to the intermediate when the intermediate member is rotated, and means carried by the base member and frictionally engaging the intermediate 60 member to yieldably resist rotation of the intermediate member.

4. A lifting jack comprising upper, lower and intermediate hollow members, the lower member being in the form of a supporting base and the upper member adapted to support a load, said intermediate member having an external cylindrical surface and an outwardly projecting annular collar at its lower end fitting slidably and rotatably within the base member, the upper 65 member telescoping slidably and rotatably within the intermediate member, means for rotating the intermediate member, means housed within the hollow members for causing the intermediate member to be moved vertically with 70 relation to the base member and the upper member to be moved vertically with relation to the intermediate member when the intermediate member is rotated, a split collar fitted within the upper end of the base member above the 75 collar on the intermediate member, there being mating openings in the base member and split collar, friction plugs movably fitted in these openings, and a spring ring engaged about the plugs and forcing them yieldably into engagement with the external cylindrical surface of the intermediate member.

5. A lifting jack comprising a supporting standard having a vertical cylindrical chamber extending through the top thereof, a lifting member telescoping within said standard, said lifting member having a cylindrical exterior surface with an outstanding annular flange at its lower end adapted to extend within the chamber in the standard, means for rotating the lifting member, means confined within the standard and lifting member for elevating or lowering the lifting member when the lifting member is rotated relative to the standard, and means carried by the standard for frictionally 80 engaging the exterior surface of the lifting member above the annular flange.

6. A lifting jack comprising a supporting standard having a vertical cylindrical chamber extending through the top thereof, a lifting member telescoping within said standard, said lifting member having a cylindrical exterior surface with an outstanding annular flange at its lower end adapted to extend within the chamber in the standard, means for rotating 85 the lifting member, means confined within the standard and lifting member for elevating or lowering the lifting member when the lifting member is rotated relative to the standard, and means carried by the standard for frictionally 90 engaging the exterior surface of the lifting member above the annular flange.

the lifting member, means confined within the standard and lifting member for elevating or lowering the lifting member when the lifting member is rotated relative to the standard, a 5 split collar adapted to fit about the cylindrical surface of the lifting member above the annular flange thereon and within the upper end portion of the standard, friction plugs movably positioned in mating openings in the upper portion 10 of the standard and the split collar, and a spring ring secured about the plugs and holding them in yielding frictional engagement with the lifting member.

7. A lifting jack comprising upper, lower and 15 intermediate hollow members, the upper member having a cylindrical external surface, a load supporting cap at the upper end of the upper member, an internally threaded nut fixed within the lower end of the upper member, the internal cavity of the upper member above the 20 nut being of non-circular cross-section, the intermediate member having a cylindrical external surface with an outwardly projecting annular collar at its lower end, means carried 25 by the upper end portion of the intermediate member for rotating the same, a hollow externally threaded screw-sleeve positioned centrally within the intermediate member and fixed thereto at its lower end, said screw-sleeve meshing 30 within the nut in the upper member, there being an internally threaded nut in the lower end of the screw-sleeve, the lower hollow member being in the form of a supporting base having a cylindrical interior in which the collar 35 at the lower end of the intermediate member is rotatable and vertically slidably, means carried by the upper end of the base member for frictionally engaging the cylindrical external surface of the intermediate member above the 40 collar thereon, a hollow externally threaded screw fixed at its lower end in the base member and meshing within the nut in the intermediate member, a non-circular post member slidably fitted within an opening of similar cross-section 45 in the upper end of the hollow screw, and a key member fixed to the upper end of the post and slidably but nonrotatably engaging within the non-circular cavity in the upper hollow member.

50 8. A lifting jack comprising upper, lower and intermediate externally cylindrical hollow members, the lower member being in the form of a supporting base and the upper member adapted to support a load, said upper member telescoping 55 slidably within the intermediate member and the intermediate member telescoping slidably within the base member, means mounted on and movable vertically with the intermediate member for rotating the intermediate member,

a screw sleeve secured within and movable with the intermediate member and internally engaging the upper member, and extensible means housed within the hollow members and secured at its lower end to the base member and movably engaging the upper member and screw sleeve internally for holding the upper member against rotation and causing the intermediate member to be moved vertically with relation to the base member and the upper member to be moved vertically with relation to the intermediate member when the intermediate member is rotated. 80

9. A lifting jack comprising upper, lower and intermediate externally cylindrical hollow members, the lower member being in the form of a supporting base and the upper member adapted to support a load, said upper member telescoping slidably within the intermediate member and the intermediate member telescoping slidably within the base member, means mounted on and movable vertically with the intermediate member for rotating the intermediate member, a screw sleeve secured within and movable with the intermediate member and internally engaging the upper member, and extensible means housed within the hollow members and secured at its lower end to the base member and having sliding engagement with the upper member and threaded engagement with the screw sleeve for holding the upper member against 95 rotation and causing the intermediate member to be moved vertically with relation to the base member and the upper member to be moved vertically with relation to the intermediate member when the intermediate member is rotated. 100

10. A lifting jack comprising upper, lower and intermediate externally cylindrical hollow members, the lower member being in the form of a supporting base and the upper member adapted to support a load, said upper member telescoping 115 slidably within the intermediate member and the intermediate member telescoping slidably within the base member, means mounted on and movable vertically with the intermediate member for rotating the intermediate member, and extensible means housed within the hollow members and comprising a plurality of members movably engaged with one another, one of the members being secured to the base member and one to the intermediate member, and the means 120 being movably engaged with the upper member so that the upper member is held against rotation and the intermediate member is caused to move vertically with relation to the base member and the upper member to move vertically 125 with relation to the intermediate member when the intermediate member is rotated. 130
